UNITED STATES PATENT OFFICE.

MURILLO DOWNER, OF CHICAGO, ILLINOIS.

AIR-CUSHION FOR CARS.

SPECIFICATION forming part of Letters Patent No. 758,604, dated April 26, 1904.

Application filed July 27, 1903. Serial No. 167,061. (No model.)

To all whom it may concern:

Be it known that I, MURILLO DOWNER, a citizen of the United States, residing at Chicago, in the county of Cook and State of Illinois, have invented a certain new and useful Improvement in Air-Cushions for Cars, of which the following is a specification.

My invention relates to improvements in air-cushions for cars and the like, and has for its object to provide certain new and useful improvements. It is illustrated in the accompanying drawings, wherein—

Figure 1 is a side view of a truck with my improvement attached. Fig. 2 is a section on the line 2 2, Fig. 1. Fig. 3 is a plan of the truck. Fig. 4 is a vertical section through the central cylinder.

Like parts are indicated by the same letter in all the figures.

20 A A are the rails on which run the car-wheels B B. The car-wheels are suitably mounted in any desired manner in the ends of the truck. This truck may consist of the bars C C, arranged as indicated and provided with 25 suitable parts to receive the ends of the car-axles D D. These bars C C are connected by a channel-bar C' and vertical pieces C'. Associated with the car-truck is a truck-bolster consisting of the bars E E, which are secured 30 together toward their outer ends by the plates E', on which are secured the plates F F and which are provided each with a raised bearing-surface F'. Secured on the channel-bar C' are the upwardly-projecting hollow plungers G and H. The plungers may be bolted 35 in position by the bolts J, and they are provided above each with a disk J' and a packing-disk J''. The plungers project, respectively, into the cylinders G' and H', and each 40 cylinder is preferably packed about the plunger by means of the packing-annulus H'' and the screw-piece H''. The plungers G and cylinders G' are placed toward the outer ends of the bolster while the plunger H and cylinder H' are placed in the middle of the bolster.

45 K is the car-bolster, secured in any desired manner to the car K', and the cylinder H' is

rigidly secured to the middle of this bolster. Projecting from the cylinder H' are the lugs L, through each of which passes the bolt L', 50 which is secured to the channel-bar at L'' and provided with a head L''' to limit the upward motion of the cylinder H'.

M M are bearing-plates on the car-bolster or car, which rest upon the plates F' F'', so as 55 to be supported thereby, but movable thereupon.

N is an air-supply pipe to supply air under pressure from any desired source.

N' is a pressure-regulating valve which permits the air to pass therethrough when the pressure is reduced on the delivery side. From N' leads the pipe N'' to the cross N'', whence lead the three connections N⁴, N⁵, and N⁶. Each leads to one of the cylinders. N⁷ 65 and N⁸ are flexible portions which allow the truck to swing without interfering with these air connections, for the pipe N is rigid with the car, while the two outer cylinders are rigid with the truck.

70 O O are check-valves which permit the air to enter the cylinders, but prevent it from returning.

P P are blow-off or safety valves, which serve to prevent too great a pressure in the 75 cylinder. The blow-off valve connected with the cylinder H' is associated with a controlling chain or link P', which is connected by a slot P² and pin P³ and arm P⁴ with the car-truck. If the amount of air in the cylinder 80 H' increases so as to lift the car, the blow-off valve P will be opened, so as to reduce the air when it is raised beyond the normal position. This device is unnecessary with the outside 85 cylinders G' G'', for they are associated with the truck-bolster, which is prevented from rising too far by the engagement of the ends of the bars E E with the under side of the upper bars C C.

90 The use and operation of my invention are as follows: Assuming the parts to be associated as described, and it will be understood that certain elements and features for the purpose of clearness in the drawings have been

omitted, though they are commonly incorporated in car trucks and devices, they will be in their normal position when they are as illustrated in the drawings. The car is therefore resting at all points on an air-cushion, because the sides of the car are supported upon the floating truck-bolster and the middle of the car is supported on the channel-bar of the truck; but in each case an air-cushion is interposed. The pressure of the air in these several cylinders is always the same, because of the action of the check-valves and the blow-off valves. If for any reason the car rises so as to reduce the pressure and bring in an extra supply of air, the pressure of course will stand at the normal when the car sinks back into position, but the car will be somewhat elevated. This action is not objectionable within limits, but of course could not be carried too far. This action is checked either by the positive stop of the ends of the bars E on the truck-pieces C or by the device for operating the safety-valve or blow-off valve P on the middle cylinder. Either device can be used separately or they can be combined, as shown in the drawings. The truck is pivoted to the car so as to swing on this central cylinder, and thus the king-bolt or pivot-bolt is dispensed with and the cushion-cylinder employed in its place.

It is obvious that various changes could be made and parts omitted or varied without departing from the spirit of my invention, and I do not wish, therefore, to be limited to the particular forms, shapes, proportions, and arrangements shown. Moreover, the structure could be applied to other than such cars and trucks as are here illustrated.

I claim—

- 40 1. In an air-cushion device for cars, the combination of a centrally-placed cylinder and plunger connecting the car and the truck and a floating bolster supporting the sides of the car.
- 45 2. In an air-cushion device for cars, the combination of a centrally-placed cylinder and plunger connecting the car and the truck, with an air-supply device therefor and a floating bolster supporting the sides of the car.
- 50 3. In an air-cushion device for cars, the combination of a centrally-placed cylinder and plunger connecting the car and the truck, with an air-supply device and an air-discharge device therefor and a floating bolster supporting the sides of the car.
- 55 4. In an air-cushion device for cars, the combination of a centrally-placed cylinder and plunger connecting the car and the truck, with an air-supply device and an air-discharge device therefor, and means for preventing the excessive rise of the car and a floating bolster supporting the sides of the car.

5. In an air-cushion device for cars, the combination of a car and truck, with a cylinder on one and a plunger on the other coacting, and an air-cushion within the cylinder and a floating bolster between car and truck with supporting air-cushions. 65

6. In an air-cushion device for cars, the combination of a car and truck, with a cylinder on one and a plunger on the other coacting, an air-cushion within the cylinder, and means for preventing the car from abnormally rising and a floating bolster between car and truck with supporting air-cushions. 70

7. In an air-cushion device for cars, the combination of a car and truck, with a cylinder on one and a plunger on the other coacting, an air-cushion within the cylinder, and means for preventing an excess of air in the cylinder and a floating bolster between car and truck with supporting air-cushions. 75

8. In an air-cushion device for cars, the combination of a car and truck, with a cylinder on one and a plunger on the other coacting, an air-cushion within the cylinder, and a discharge-valve connected with the cylinder to discharge the air therefrom and a floating bolster between car and truck with supporting air-cushions. 80

9. In an air-cushion device for cars, the combination of a car and truck, with a cylinder on one and a plunger on the other coacting, an air-cushion within the cylinder, a discharge-valve connected with the cylinder to discharge the air therefrom, and means for automatically opening said valve when the car has reached a predetermined elevation and a floating bolster between car and truck with supporting air-cushions. 90

10. In an air-cushion device for cars, the combination of a truck, with a floating bolster, an air-cushion between the bolster and the truck, and a direct connection between the truck and the car intermediate between the ends of the bolster. 105

11. In an air-cushion device for cars, the combination of a truck, with a floating bolster, an air-cushion between the bolster and the truck, and an air-cushioned direct connection between the truck and the car intermediate between the ends of the bolster. 110

12. In an air-cushion device for cars, the combination of a truck, with a floating bolster, an air-cushion between the two, and bearings for the car toward the ends of the bolster. 115

13. In an air-cushion device for cars, the combination of a truck, with a floating bolster, an air-cushion between the two, bearings for the car toward the ends of the bolster, and a central connection between the car and the truck. 120

14. In an air-cushion device for cars, the combination of a truck, with a floating bol-

ster, an air-cushion between the two, bearings for the car toward the ends of the bolster, and a central pivotal connection between the car and the truck.

5 15. In an air-cushion device for cars, the combination of a truck, with a floating bolster, an air-cushion between the two, bearings for the car toward the ends of the bolster, a

central pivotal connection between the car and the truck, and an air-cushion associated with such connection.
